UNITED STATES PATENT OFFICE.

NORMAN LIPSKY, OF NEW YORK, N. Y., ASSIGNOR TO RELIANCE METAL SPINNING & STAMPING CO., INC., OF BROOKLYN, NEW YORK, A CORPORATION OF NEW YORK.

DESIGN FOR A LAMP.

51,902.

Specification for Design.

Patented Mar. 26, 1918.

Application filed December 4, 1917. Serial No. 205,471. Term of patent 3½ years.

To all whom it may concern:

Be it known that I, NORMAN LIPSKY, a citizen of Russia, residing in the city of New York, borough of Manhattan, in the county and State of New York, have invented a new, original, and ornamental Design for a Lamp, of which the following is a specification, reference being had to the accompanying drawing, forming part thereof.

The figure is a perspective view of a lamp showing my new design.

I claim:

The ornamental design for a lamp as shown.

NORMAN LIPSKY.
